Application April 29, 1942, Serial No. 440,916

6 Claims. (Cl. 273—155)

This invention relates to a puzzle of the type in which planar pieces having printed or otherwise applied indicia or designs appearing thereon are assembled so as to produce a desired picture or arrangement of subject-matter which is the object of the puzzle.

The improved form of puzzle may be cheaply manufactured and sold as it comprises a relatively small number of pieces all of the same size and shape.

One of the principal objects of the invention is to provide a puzzle composed of a plurality of flat, flexible strips which are assembled to complete the puzzle by overlapping and interweaving the strips, the total surface area of the completed puzzle being half as large as the total surface area of the individual strips, half of the strips being laid side by side horizontally and the other half of the strips being laid side by side vertically, the horizontal and vertical strips being, respectively, interwoven to properly solve the puzzle.

An important advantage of a puzzle of this type is that a series of puzzles may be produced in all of which the pieces are fitted together in a similar manner, the subject-matter appearing on the puzzle pieces; however, being arranged to produce a variety of different effects to hold the appeal and interest of the users and to provide a range in the time required to work out the puzzle.

Since the strips which comprise the puzzle are designed to be assembled by interweaving or overlapping certain portions of the puzzle strips with portions of the other puzzle strips, certain areas or portions of the puzzle strips will be covered up when the puzzle is completed and it is a feature of our invention that such concealed areas or portions may have designs or portions of designs printed thereon in a manner to constitute false clues or decoy elements which add to the difficulty of discovering the proper solution of the puzzle.

Further objects and advantages of the improvements in a puzzle will be more readily apparent from the following description of a preferred embodiment thereof as illustrated in the attached drawings in which:

Fig. 1 is a plan view of a picture showing an arrangement of fish designs which is the object of one embodiment of the improved puzzle;

Fig. 2 is a plan view showing the several pieces of the fish design puzzle before the pieces are put together;

Fig. 3 is a plan view showing the puzzle in an incomplete stage;

Fig. 4 is a plan view showing the completed puzzle in which the arrangement of the visible fish design elements correspond to that of Fig. 1;

Fig. 5 is a plan view showing the pieces of a puzzle in which letters are displayed on the faces of the puzzle pieces;

Fig. 6 is a plan view showing the pieces of Fig. 5 assembled to complete the puzzle;

Fig. 7 is a plan view of the pieces of a puzzle in which the pieces have design elements intended to appear in the completed puzzle and other design elements different in character which are intended to be concealed in the completed puzzle;

Fig. 8 is a plan view showing the pieces of Fig. 7 assembled to complete the puzzle;

Fig. 9 is a plan view showing puzzle pieces of a further embodiment of the puzzle; and

Fig. 10 is a plan view of the puzzle pieces of Fig. 9 assembled to form the completed puzzle.

The puzzle disclosed in Figs. 1 to 4 will first be described. In this type of puzzle, the picture designated 10 in Fig. 1 shows a certain arrangement of a plurality of design elements, in this instance comprising fishes 11. Other designs and arrangements could be used. The object of the puzzle is to combine the puzzle pieces of Fig. 2 so that the fish elements appearing thereon are displayed in the same manner as in Fig. 1. The ten puzzle pieces in Fig. 2 are identified as 12 to 21 inclusive. Each of the puzzle pieces is a flexible paper strip having a length five times its width. It should be understood that half of the puzzle pieces will be laid horizontally while the other half of the puzzle pieces will be laid vertically to complete the puzzle. The pieces 12 to 16 inclusive are the vertically disposed pieces in Fig. 4 while the pieces 17 to 21 inclusive are the horizontally disposed pieces in Fig. 4. It will be noted that each of the pieces 12 to 21 have one or more fish elements appearing thereon and that there are more of these elements than are required to make the picture of Fig. 1. Some of the fish elements on the pieces will be covered up or concealed in the completed puzzle. In Fig. 2 the fish elements which remain visible when the puzzle is completed are indicated 22a to 22h inclusive. The other fish design elements, which may be termed decoys or false clues, are designated 23.

Fig. 3 illustrates the puzzle in a partial stage in which the strips 12 and 13 have been laid vertically and the strips 17 and 18 have been laid horizontally. It will be noted that the strip 17

extends over the upper end of the vertical strip 13 and under the upper end of the vertical strip 12. The horizontal strip 19 extends under the strip 13 and over the strip 12. Thus certain of the design elements which appear on the strips 12, 17 and 19 are covered up by the overlapping portions of the other strips. When the puzzle is completed as in Fig. 4, if the square is considered as divided into twenty-five smaller square units of area, each of the smaller squares is made up of overlapping portions of a vertical and a horizontal strip. In some cases the horizontal strip is on the upper side while in other cases the vertical strip is on the upper side. The puzzle pieces may therefore be described as having a total surface area which is twice as great as the surface area of the completed puzzle.

It will be understood that the pieces in Fig. 2 have been arranged in order for convenience of illustration but that when it is attempted to work out the puzzle the pieces are all mixed up making it difficult to determine the proper arrangement or order of the pieces requiring trial and error to solve the puzzle. The presence of the many decoy elements or false clues add to the difficulty of working out the puzzle. Apart from any guide that is obtained from the arrangement of the pieces or other subject-matter on the puzzle strips, each of the strips might be used as a horizontal or vertical strip making ten possible positions, and in each position the strip may be turned end for end making twenty possible arrangements for each piece. Finally each piece, even when the particular location is found, may be interwoven with the other strips in a variety of different ways. The number of possible arrangements of the pieces may therefore be considerable. For example, to illustrate the difficulty of starting the puzzle, if it is attempted to select a piece displaying the design element 22a in Fig. 4, any one of the pieces 12, 14, 17 or 21 could be tried as a horizontal strip, while none of the strips could be used vertically to display the fish elements 22a in the correct position. For the design element 22b, either strip 18 or 20 could be tried horizontally while only strip 19 could be tried vertically. For the design element 22c, strips 15, 17, 18 or 20 could be tried horizontally while only strip 19 could be tried in a vertical position.

The puzzles may take a number of different forms in each of which the pieces may be similar in size and shape and assembled in much the same manner, but the theme or object of the puzzle may be made different so as to maintain the interest and appeal in working out the puzzles. Several different variations have been illustrated.

Figs. 5 and 6 illustrate the puzzle in a form in which letters appear on the puzzle pieces and when the puzzle is put together the letters are combined to spell words. For example, the puzzle pieces identified as 32 to 41 inclusive in Fig. 5 are assembled to complete the puzzle as shown in Fig. 6. In this case the object of the puzzle is to spell out the slogan "All's Well that Ends Well," and it is not necessary to have a picture or guide such as in Fig. 1 of the first embodiment of the puzzle. The letters on the puzzle are displayed thereon in a variety of positions to increase the difficulty of determining the position of a particular piece. There are more letters than required to make the words appearing in Fig. 6.

Similarly, in Figs. 7 and 8 a different type of puzzle is illustrated in which the puzzle pieces

42 to 51 inclusive of Fig. 7 are combined to form the completed puzzle as in Fig. 8. In this case the puzzle pieces have certain figures, such as the girl figures shown, which appear in the completed puzzle, whereas all the other figures, such as the circular figures shown on the puzzle pieces, are concealed in the completed puzzle. The object of this puzzle is to arrange the pieces so that all of the circular figures are covered up while all of the girl figures are visible in the completed puzzle.

In Figs. 9 and 10 the puzzle pieces identified as 52 to 61 inclusive in Fig. 9 are assembled to complete the puzzle shown in Fig. 10. In this case a guide may be given showing that a cottage figure is in the upper left hand corner of the completed puzzle while the man figure is in the lower right hand corner of the completed puzzle and it is stated that in the completed puzzle there will appear a continuous path from the cottage figure to the man figure passing through each of the smaller square units of area of the entire puzzle. It will be understood that the paths appearing on the individual puzzle pieces are more than sufficient to form the path shown in Fig. 10 and therefore that certain portions of the puzzle pieces must be covered up by overlapping portions of other pieces.

When the completed puzzle forms a square any even number of pieces could be used. Thus, sixteen pieces could be combined into a square having eight horizontal and eight vertical strips, each strip being eight times as long as its width.

It will be understood that the puzzle need not be limited to an embodiment in which the completed puzzle is square. The final form could be a rectangle, circle, triangle or other configuration but in such cases the strips would not all be of the same size and shape and the puzzle would be relatively more easy to work out. Also it will be understood that in the square form of puzzle the strips need not run vertically and horizontally but could run diagonally of the square, being interwoven or interlapped in a similar manner. Here again the strips would not all be of the same size and shape. Since the puzzle strips must be bent to interweave and interfit, it is desirable that they be made of some flexible material, for example, stiff paper or cardboard.

In making the puzzle initially, a plurality of strips could be cut to the size and shape of the strips shown in Fig. 2. The strips could then be assembled in some haphazard interweaving and overlapping arrangement. The visible faces of the pieces are then marked to correspond to corresponding portions of the picture or arrangement which is the object of the puzzle. The pieces are then separated and the concealed portions marked to have false clues thereon. Reproductions of the puzzle strips are made in any suitable manner.

We claim:

1. A puzzle comprising a plurality of separate strips all of the same size and shape, each of said strips having indicia appearing thereon, only certain portions of said indicia being required to work out the puzzle and the remaining portions of said indicia affording false clues, the indicia which affords false clues being exactly similar to indicia displayed on other pieces but in different relative position, said strips being designed for assembly by laying part of said strips in side by side relationship and the remainder of said strips also in side by side relationship but cross-wise with respect to the first mentioned strips,

said crosswise strips being interwoven at least in part with the first mentioned strips.

2. A puzzle comprising a plurality of separate strips all of the same size and shape, each of said strips having letters thereon, said letters being turned at various angles with respect to any one side of the puzzle strip and only certain of said letters being required to work out the puzzle, said strips being designed for assembly by laying half of said strips in side by side relationship and the remaining half of said strips also in side by side relationship but crosswise with respect to said first mentioned strips, said crosswise strips being interwoven at least in part with the first mentioned strips whereby the letters which are visible in the completed puzzle are arranged to form words.

3. A puzzle comprising a plurality of separate strips all of the same size and shape, each of said strips having paths or portions of paths appearing thereon, the paths being more than sufficient to properly work out the puzzle, certain portions of said paths being exactly duplicated on more than one strip to afford a false clue as to which strip should be used to display the duplicate portion of the pattern, said pieces being designed for assembly by laying half of said strips in side by side relationship and the remaining half of said strips also in side by side relationship but crosswise with respect to said first mentioned strips to form a square, said crosswise strips being interwoven at least in part with said first mentioned strips, the portions of the strips which remain visible in the completed puzzle displaying a continuous path between at least two corners of the square.

4. A puzzle comprising an even number of pieces, each piece consisting of a flexible rectangular strip, all of the pieces being of the same size and shape, each strip having square units of area equal in number to half the number of pieces, each strip having indicia applied to at least one unit area thereof, the units of area to which said indicia is applied being more than half the total unit area of all the pieces, certain of said indicia being displayed on more than one piece, the completion of the puzzle being carried out by selecting half of the pieces to be arranged horizontally in side-by-side relationship and the remaining half of the pieces to be arranged vertically in similar side-by-side relationship and interweaving the horizontal and vertical pieces in a definite but irregular pattern

whereby the assembled pieces form a square the exposed face of which makes a desired complete design in which each piece of the puzzle has at least one unit area thereof exposed and at least one unit area thereof concealed by an overlapping piece, certain of the indicia being applied to a piece in such a manner that the piece might be used in either a horizontal or vertical position although there is only one correct position therefor, the indicia which affords a false clue as to the relative position of the piece being covered up in the complete puzzle.

5. A puzzle comprising an even number of pieces, each piece consisting of a flexible strip rectangular in shape, all of the pieces being of the same size and shape, the pieces being adapted to be assembled by laying half of the strips horizontally in side-by-side relationship and in a definite order and the remaining half of the strips vertically in similar side-by-side relationship and in a definite order and interweaving the respective horizontal and vertical strips in a definite but irregular pattern, whereby the exposed portions of the pieces in the completed puzzle form a square, each piece having indicia displayed thereon comprising fragmentary portions of the complete design appearing on the face of the completed puzzle, certain portions of said indicia being duplicated on more than one piece to afford false clues as to whether a particular strip should be arranged horizontally or vertically, said indicia which constitutes a false clue being covered up by an overlapping strip in the completed puzzle.

6. A puzzle comprising a plurality of separate strips all of the same size and shape, each of said strips having one or more figures appearing thereon, all of said figures being similar in appearance but being arranged in a plurality of relative positions, only certain of said figures being required to work out the puzzle, said strips being designed for assembly by laying half of said strips in side-by-side relationship and the remaining half of said strips also in side-by-side relationship but crosswise with respect to said first mentioned strips, said crosswise strips being interwoven at least in part with the first mentioned strips whereby the figures which appear on the face of the completed puzzle are displayed in the desired pattern and the figures which are not used are concealed by overlapping strips.
